ELECTRIC AUTOMATIC OPERATING APPARATUS FOR MECHANICAL SPEED CHANGING DEVICES, PARTICULARLY FOR MOTOR CARS

Aldo Filocamo, Milan, Italy

Application May 15, 1951, Serial No. 226,466
In Italy November 9, 1950

12 Claims. (Cl. 74—365)

1

The present invention relates to electrical automatic apparatus for operating speed changing devices, particularly used for motor cars.

The invention involves a change speed device comprising a plurality of electromagnetic means for operating various gears in a gearbox, and at least one electromagnetic member actuated by a voltage, and whose core is displaced according to the height of said tension supplied by a generator driven by the transmission so as to actuate a movable contact which closes successively, and in a certain order, the circuits of said electromagnetic operating members according to the speed attained by the vehicle.

The invention will be described with reference to the accompanying schematic drawing, which is given only as an example of the invention without any restrictive intention of the application of the same.

In the drawing:

Fig. 1 shows in a longitudinal section one form in accordance with construction of the invention;

Fig. 2 shows a detail of the electromagnetically operated movable contact.

With reference to said figures, A indicates the box containing the movable members of the speed changing mechanism, which, in the example illustrated, comprises a shaft 2 which is driven by motor E of the vehicle, and driving through gear couple 4, the secondary shaft 6. Drive or primary shaft 8 is arranged coaxial with shaft 2. To shaft 8 is fastened the four gears 10, 12, 14 and 16 intended to cooperate with the corresponding gears 10', 12', 14', and 16' which are loose on secondary shaft 6.

Gear couples 12, 12', 14, 14', and 16, 16' represent respectively the 1st, 2nd and 3rd speed. The 4th speed and/or direct drive is obtained by coupling shafts 2 and 8 by torsional toothed coupling 18. To the end of torsionally binding one or the other of gears 10', 12', 14' and 16' to shaft 6 for obtaining the different ratios of transmission, each of said gears is provided with a front set of teeth 20 which cooperate with a corresponding toothed sleeve 22, torsionally bound to shaft 6 but axially movable on the latter. Axial sliding of sleeves 22 and of the movable part of torsional coupling 18 of the direct drive is obtained through electromagnets 24, 26, 28, 30, 32 whose cores determine the oscillation of a forked lever 36 in contrast with spring return means 34.

Closing of the circuit for the automatic insertion of the electromagnets (Fig. 2) is obtained

2

through a movable timing contact 38 which contacts, two at a time, four couples of stationary contacts 40, 42; 44, 46 located onto a sector C made of electrical insulating material.

Movable contact 38 is carried by a rotatable oscillating arm 48 on shaft 50, to which is rigidly connected a second arm 52 and a toothed pinion 54. The latter cooperates with a rack 56 actuated by an electromagnet 58 fed by generator 60 which in turn is operatively connected to primary shaft 8. Arm 52 has two drag catches 62 and 64 arranged laterally to arm 48. The two arms are connected by means of a spring means 66.

Right hand contacts (Fig. 1) of the couples carried by sector C are electrically connected through a conductor 68 to the direct current generator 70 driven by motor B of the vehicle.

Left hand stationary contacts are connected in the circuits as follows:

Conductor 72 connects 40 with the movable contact of a deviator 74
Conductor 76 connects 42 to electromagnet 28
Conductor 78 connects 44 to electromagnet 30
Conductor 80 connects 46 to electromagnet 32

The two stationary contacts of the deviator are connected one (82) to electromagnet 24 and the other (84) to electromagnet 26. The four positions of contact of arm 48 are determined by as many spring balls 86 located in body C and intended to collaborate with a notch in arm 48.

The mechanism works as follows: At rest the organs are in the position illustrated. For starting a head deviator 74 is manually displaced to contact 82 closing the circuit in which electromagnet 26 is connected. The latter is fed by generator 60, and determines the torsional engagement of gear 12' with shaft 6 by causing arm 36 to oscillate, thus inserting the first speed. For the reverse speed, deviator 74 is placed on contact 84 by sending the current to electromagnet 24 which acts upon reverse gears 10.

When moving generator 60 generates current, the latter feeding electromagnet 58 which results in the attraction of core 91 (Fig. 2) and tends to shift axially rack 56 according to arrow X. Arm 52 then rotates according to arrow Y charging spring 66, until finger 62, acting on arm 48, frees it from the engagement of spring charged positioning ball 86. Spring 66, when unbiased, produces a quick displacement of arm 48 over contacts 42 which feeds electromagnet 28 thus engaging second speed. At the same time, the opening of circuit of electromagnet 26

brings about the disengagement, by means of opposing spring 34, of the first speed.

During acceleration of the vehicle the current generated by dynamo 60 increases and therefore increases the extent of the displacement of rack 66 in opposition to the return spring means 88 (that presses onto the rack in a direction opposed to arrow X).

Then, immediately, and automatically thereafter, the higher speeds are engaged (3rd and 10 direct drive). The speed range is suitably chosen in proportion to the speed of the vehicle by modifying the setting of opposing spring 88. An electric setting means may be used which varies the electrical resistance of the feed circuit of electromagnet 58 by inserting a variable resistor 90, and consequently varying the attractive force of electromagnet 58 at the same speed of generator 62.

The insertion of variable resistance 90 (under normal circumstances not inserted) produces a lowering of the tension to feed electromagnet 58, and is intended to prevent the leap to a higher speed in cases of emergency (winding, steep descents) thus obtaining motor braking.

The same sequence of operations is evidently obtained in an opposite sense when the vehicle slows down.

I claim:

1. A change speed device, comprising, in combination, a change speed gear including a plurality of gears and a shaft carrying one wheel of each of said gears; a plurality of electromagnetic means actuating, respectively, said gears of said change speed gear; an electromagnet having an armature having a plurality of positions depending on the voltage energizing said electromagnet; a D. C. generator driven by said shaft of said change speed gear and having an output voltage depending on the speed of said shaft; means for feeding the output voltage of said D. C. generator to said electromagnet so as to energize the same by the output voltage of said D. C. generator; at least one movable contact controlled by said armature; and a plurality of stationary contacts connected, respectively, to said electromagnetic means actuating said gears of said change speed gear, said movable contact being arranged for cooperation with said stationary contacts so as to make contact with the same one at a time, whereby the output voltage of said D. C. generator and thus the position of said armature depend on the speed of said shaft, thereby actuating automatically said gears of said change speed gear according to the speed of said shaft.

2. A change speed device, comprising, in combination, a change speed gear including a plurality of gears and a shaft carrying one wheel of each of said gears; a plurality of electromagnetic means actuating, respectively, said gears of said change speed gear; an electromagnet having an armature having a plurality of positions depending on the voltage energizing said electromagnet; a D. C. generator driven by said shaft of said change speed gear and having an output voltage depending on the speed of said shaft; means for feeding the output voltage of said D. C. generator to said electromagnet so as to energize the same by the output voltage of said D. C. generator; an oscillating arm controlled by said armature; at least one movable contact; resilient means connecting said movable contact with said oscillating arm; and a plurality of stationary contacts connected, respectively, to said electromagnetic means actuating said gears of said change speed

gear, said movable contact being arranged for cooperation with said stationary contacts so as to make contact with the same one at a time, whereby the output voltage of said D. C. generator and thus the position of said armature depend on the speed of said shaft, thereby actuating automatically said gears of said change speed gear according to the speed of said shaft.

3. A change speed device, comprising, in combination, a change speed gear including a plurality of gears and a shaft carrying one wheel of each of said gears; a plurality of electromagnetic means actuating, respectively, said gears of said change speed gear; an electromagnet having an armature having a plurality of positions depending on the voltage energizing said electromagnet; a D. C. generator driven by said shaft of said change speed gear and having an output voltage depending on the speed of said shaft; means for feeding the output voltage of said D. C. generator to said electromagnet so as to energize the same by the output voltage of said D. C. generator; an oscillating arm controlled by said armature; at least one movable contact; resilient means connecting said movable contact with said oscillating arm; a plurality of stationary contacts connected, respectively, to said electromagnetic means actuating said gears of said change speed gear, said movable contact being arranged for cooperation with said stationary contacts so as to make contact with the same one at a time; and a plurality of spring-loaded means securing, respectively, said movable contact in positions for cooperation with said stationary contacts, said spring-loaded means being weaker than said resilient means so as to be rendered ineffective when said oscillating arm has a position with respect to said movable contact stretching said resilient means, whereby the output voltage of said D. C. generator and thus the position of said armature depend on the speed of said shaft, thereby actuating automatically said gears of said change speed gear according to the speed of said shaft.

4. A change speed device, comprising, in combination, a change speed gear including a plurality of gears and a shaft carrying one wheel of each of said gears; a plurality of electromagnetic means actuating, respectively, said gears of said change speed gear; an electromagnet having an armature having a plurality of positions depending on the voltage energizing said electromagnet; a D. C. generator driven by said shaft of said change speed gear and having an output voltage depending on the speed of said shaft; means for feeding the output voltage of said D. C. generator to said electromagnet so as to energize the same by the output voltage of said D. C. generator; an oscillating arm controlled by said armature; at least one movable contact arranged for relative motion with play relative to said oscillating arm between a first and a second end position; resilient means connecting said movable contact with said oscillating arm; a plurality of stationary contacts connected, respectively, to said electromagnetic means actuating said gears of said change speed gear, said movable contact being arranged for cooperation with said stationary contacts so as to make contact with the same one at a time; and a plurality of spring-loaded means securing, respectively, said movable contact in positions for cooperation with said stationary contacts, said spring-loaded means being weaker than said resilient means so as to be rendered ineffective when said oscillating arm has one of said positions relative to said movable contact

stretching said resilient means, whereby the output voltage of said D. C. generator and thus the position of said armature depend on the speed of said shaft, thereby actuating automatically said gears of said change speed gear according to the speed of said shaft.

5. A change speed device, comprising, in combination, a change speed gear including a plurality of gears and a shaft carrying one wheel of each of said gears; a plurality of electromagnetic means actuating, respectively, said gears of said change speed gear; an electromagnet having an armature having a plurality of positions depending on the voltage energizing said electromagnet; resilient means connected to said armature, said resilient means opposing the action of said electromagnet on said armature; a D. C. generator driven by said shaft of said change speed gear and having an output voltage depending on the speed of said shaft; means for feeding the output voltage of said D. C. generator to said electromagnet so as to energize the same by the output voltage of said D. C. generator; at least one movable contact controlled by said armature; and a plurality of stationary contacts connected, respectively, to said electromagnetic means actuating said gears of said change speed gear, said movable contact being arranged for cooperation with said stationary contacts so as to make contact with the same one at a time, whereby the output voltage of said D. C. generator and thus the position of said armature depend on the speed of said shaft, thereby actuating automatically said gears of said change speed gear according to the speed of said shaft.

6. A change speed device, comprising, in combination, a change speed gear including a plurality of gears and a shaft carrying one wheel of each of said gears; a plurality of electromagnetic means actuating, respectively, said gears of said change speed gear; an electromagnet having a winding and an armature having a plurality of positions depending on the voltage energizing said electromagnet; a D. C. generator driven by said shaft of said change speed gear and having an output voltage depending on the speed of said shaft; means for feeding the output voltage of said D. C. generator to said winding of said electromagnet so as to energize the same by the output voltage of said D. C. generator; at least one variable resistor connected in series with said winding of said electromagnet; at least one movable contact controlled by said armature; and a plurality of stationary contacts connected, respectively, to said electromagnetic means actuating said gears of said change speed gear, said movable contact being arranged for cooperation with said stationary contacts so as to make contact with the same one at a time, whereby the output voltage of said D. C. generator and thus the position of said armature depend on the speed of said shaft, thereby actuating automatically said gears of said change speed gear according to the speed of said shaft.

7. A change speed device, comprising, in combination, a change speed gear including a plurality of gears and a shaft carrying one wheel of each of said gears; a plurality of electromagnetic means actuating, respectively, said gears of said change speed gear; an electromagnet having an armature having a plurality of positions depending on the voltage energizing said electromagnet; a D. C. generator driven by said shaft of said change speed gear and having an output voltage depending on the speed of said shaft; means for

feeding the output voltage of said D. C. generator to said electromagnet so as to energize the same by the output voltage of said D. C. generator; an oscillating arm; a pinion rigidly connected with said oscillating arm; a rack cooperating with said pinion, said rack being controlled by said armature; at least one movable contact; resilient means connecting said movable contact with said oscillating arm; and a plurality of stationary contacts connected, respectively, to said electromagnetic means actuating said gears of said change speed gear, said movable contact being arranged for cooperation with said stationary contacts so as to make contact with the same one at a time, whereby the output voltage of said D. C. generator and thus the position of said armature depend on the speed of said shaft, thereby actuating automatically said gears of said change speed gear according to the speed of said shaft.

8. A change speed device, comprising in combination, a change speed gear including a plurality of gears for forward drive, a gear for reverse drive, and a shaft carrying one wheel of each of said gears; a plurality of electromagnetic means actuating, respectively, said gears of said change speed gear; an electromagnet having an armature having a plurality of positions depending on the voltage energizing said electromagnet; a D. C. generator driven by said shaft of said change speed gear and having an output voltage depending on the speed of said shaft; means for feeding the output voltage of said D. C. generator to said electromagnet so as to energize the same by the output voltage of said D. C. generator; at least one movable contact controlled by said armature; a plurality of stationary contacts connected, respectively, to said electromagnetic means actuating said gears for forward drive of said change speed gear, said movable contact being arranged for cooperation with said stationary contacts so as to make contact with the same one at a time; and a double-throw switch having a first position and a second position, said double-throw switch connecting in the first position thereof one of said stationary contacts to one of said gears for forward drive and in the second position thereof said one stationary contact to said gear for reverse drive, whereby the output voltage of said D. C. generator and thus the position of said armature depend on the speed of said shaft, thereby actuating automatically said gears of said change speed gear according to the speed of said shaft.

9. A self-propelled vehicle, comprising, in combination, a motor; a first D. C. generator driven by said motor; a change speed gear driven by said motor and including a plurality of gears and a shaft carrying one wheel of each of said gears; a plurality of electromagnetic means actuating, respectively, said gears of said change speed gear; means for connecting said electromagnetic means one at a time to said first D. C. generator, said connecting means including first stationary contacts connected to said first D. C. generator and second stationary contacts connected, respectively, to said electromagnetic means; at least one movable contact having a plurality of positions connecting, respectively, said first stationary contacts with said second stationary contacts, one at a time; an electromagnet having an armature having a plurality of positions depending on the voltage energizing said electromagnet, said armature controlling the positions of said movable contact; a second D. C. generator driven by said shaft of said change speed gear and having

an output voltage depending on the speed of said shaft; and means for feeding the output voltage of said second D. C. generator to said electromagnet so as to energize the same by the output voltage of said second D. C. generator, whereby the output of said second D. C. generator and thus the position of said armature depends on the speed of said shaft, thereby actuating automatically said gears of said change speed gear according to the speed of said shaft.

10. A self-propelled vehicle, comprising, in combination, a motor; a first D. C. generator driven by said motor; a change speed gear driven by said motor and including a plurality of gears and a shaft carrying one wheel of each of said gears; a plurality of electromagnetic means, actuating, respectively, said gears of said change speed gear; means for connecting said electromagnetic means one at a time to said first D. C. generator, said connecting means including first stationary contacts connected to said first D. C. generator and second stationary contacts connected, respectively, to said electromagnetic means; at least one movable contact having a plurality of positions connecting, respectively, said first stationary contacts with said second stationary contacts, one at a time; an electromagnet having an armature having a plurality of positions depending on the voltage energizing said electromagnet; an oscillating arm controlled by said armature; resilient means connecting said movable contact with said oscillating arm so as to control the position of said movable contact by said armature; a second D. C. generator driven by said shaft of said change speed gear and having an output voltage depending on the speed of said shaft; and means for feeding the output voltage of said second D. C. generator to said electromagnet so as to energize the same by the output voltage of said second D. C. generator, whereby the output of said second D. C. generator and thus the position of said armature depends on the speed of said shaft, thereby actuating automatically said gears of said change speed gear according to the speed of said shaft.

11. A self-propelled vehicle, comprising, in combination, a motor; a first D. C. generator driven by said motor; a change speed gear driven by said motor and including a plurality of gears and a shaft carrying one wheel of each of said gears; a plurality of electromagnetic means actuating, respectively, said gears of said change speed gear, each of said electromagnetic means including a first electromagnet having an armature and resilient means acting upon said armature in opposition to said first electromagnet; couplings actuated, respectively, by said armatures of said first electromagnets for actuating, respectively, said gears of said change speed gear; means for connecting said first electromagnets one at a time to said first D. C. generator, said connecting means including first stationary contacts connected to said first D. C. generator and second stationary contacts connected, respectively, to said first electromagnets; at least one movable contact having a plurality of positions connecting, respectively, said first stationary contacts with said second stationary contacts, one at a time; a second electromagnet having an armature having a plurality of positions depending on the voltage energizing said second electromagnet, said armature controlling the positions of

said movable contact; a second D. C. generator driven by said shaft of said change speed gear and having an output voltage depending on the speed of said shaft; and means for feeding the output voltage of said second D. C. generator to said second electromagnet so as to energize the same by the output voltage of said second D. C. generator, whereby the output of said second D. C. generator and thus the position of said armature of said second electromagnet depends on the speed of said shaft, thereby actuating automatically said gears of said change speed gear according to the speed of said shaft.

12. A self-propelled vehicle, comprising, in combination, a motor; a first D. C. generator driven by said motor; a change speed gear driven by said motor and including a plurality of gears and a shaft carrying one wheel of each of said gears; a plurality of electromagnetic means, actuating, respectively, said gears of said change speed gear, each of said electromagnetic means including a first electromagnet having an armature and resilient means acting upon said armature in opposition to said first electromagnet; couplings actuated, respectively, by said armatures of said first electromagnets for actuating, respectively, said gears of said change speed gear; means for connecting said first electromagnets one at a time to said first D. C. generator, said connecting means including first stationary contacts connected to said first D. C. generator and second stationary contacts connected, respectively, to said first electromagnets; at least one movable contact having a plurality of positions connecting, respectively, said first stationary contacts with said second stationary contacts, one at a time; a second electromagnet having an armature having a plurality of positions depending on the voltage energizing said second electromagnet; an oscillating arm controlled by said armature of said second electromagnet; resilient means connecting said movable contact with said oscillating arm so as to control the position of said movable contact by said armature of said second electromagnet; a second D. C. generator driven by said shaft of said change speed gear and having an output voltage depending on the speed of said shaft; and means for feeding the output voltage of said second D. C. generator to said second electromagnet so as to energize the same by the output voltage of said second D. C. generator, whereby the output of said second D. C. generator and thus the position of said armature of said second electromagnet depends on the speed of said shaft, thereby actuating automatically said gears of said change speed gear according to the speed of said shaft.
